UNITED STATES PATENT OFFICE.

LEWIS C. MYERS, OF NEW YORK, N. Y., ASSIGNOR TO ROYAL TYPEWRITER COMPANY, INC., OF NEW YORK, N. Y., A CORPORATION OF NEW YORK.

LABEL-CLIP FOR TYPE-WRITING MACHINES.

1,207,199.

Specification of Letters Patent.

Patented Dec. 5, 1916.

Application filed September 24, 1914. Serial No. 863,259.

To all whom it may concern:

Be it known that I, LEWIS C. MYERS, a citizen of the United States of America, residing in the borough of Brooklyn, city of New York, county of Kings, and State of New York, have invented a new and useful Label-Clip for Type-Writing Machines, of which the following is a specification.

The label clip forming the subject of this invention consists of a thin metal plate comparatively short and transversely curved to extend partly along and fit the curvature of the platen, but sufficiently long to hold the longest label to be printed on the platen, a lever arm pivotally connected to a body piece or bracket adapted to seat on either one of the hubs at the ends of the platen, a spring clamp secured to the body piece adapted to firmly grip the hub and providing means for the ready attachment to and removal of the clip from the platen, a spring for holding the clip against the platen, a manipulating knob or handle by means of which the clip may be moved away from the platen and a stop on the lever arm for limiting the distance the clip plate can be set away from the platen. The device is so constructed that, when applied to a platen, labels may be securely held thereon and no obstruction offered to the proper working of the machine.

A practical embodiment of the invention is illustrated in the accompanying drawings in which:

Figure 1 is a perspective view of a label clip made according to this invention applied to a platen of a typewriting machine. Fig. 2, an end view of the same; and Fig. 3, a view similar to Fig. 2, showing a paper pan and pressure roller and the label clip in a position to pass freely by them.

The platen 4 is of any of the usual constructions with end hubs 5 by which it is held on the shaft 6. The clip 7 is composed of a thin metal plate transversely curved to fit the curvature of the platen and, when held against the platen or with a label, (as indicated at 8), between it and the platen, it passes without obstruction by the pressure roller 9 and paper pan 10, as shown by the dotted lines 11, Fig. 3. The clip plate 7 is by one end, which is bent at right angles to the main curved position, secured to a lever arm 12 pivoted at 13 to the upwardly extending part of a bracket in the form of an

angle-piece 14, the other part of which is formed to seat on a hub 5 of the platen. Secured to the bracket 14 by a screw 15 is a spring clamp 16 formed to firmly embrace the sides of the hub 5. The clip plate 7 is held in operative position by a spring 17 fastened between the forward end of the lever arm 12 and one edge of the spring clamp 16. A knob or handle 18 extends from the lever arm 12 and by means of which the clip plate may be manually moved away from the platen for applying labels between the clip and the platen. A tail piece 19 at the rear of the lever arm 12 acts as a stop by contacting with the bracket 14 to limit the open position of the clip 7 on the platen.

This device affords a simple and effective means for holding labels and other small sheets, either above or below the clip plate, on the rotary platen of typewriting machines and, as will be observed from its construction, it may be instantly applied to and removed from the platen.

I claim:

1. A label clip for typewriting machines, comprising a thin metal plate adapted to lie close to the periphery of the platen and to extend part-way across it from one end, and means for pivotally mounting the plate at one end of the platen to move about an axis parallel with that of the platen and for detachably connecting it therewith. 80

2. A label clip for typewriting machines, comprising a thin metal plate adapted to extend part-way across the platen at one end, a bracket to which the plate is pivotally connected to move about an axis parallel with that of the platen, and means for detachably connecting the bracket to the platen at one end thereof. 90

3. A label clip for typewriting machines, comprising a thin metal plate, a bracket, a lever to which the plate is attached and which is pivotally connected with the bracket to move about an axis parallel with that of the platen, and means for securing the bracket to the platen. 100

4. A label clip for typewriting machines, comprising a thin metal plate, a lever to which it is secured, a bracket to which the lever is pivotally connected to move about an axis parallel with that of the platen, and means for detachably connecting the bracket with the hub of a platen. 105

5. The combination with the platen of a 110

typewriting machine of a label clip, comprising a thin metal plate, a lever to which it is attached, a bracket at the end of the platen to which the lever is pivotally connected, and a spring clip attached to the bracket and engaging a hub of the platen.

6. The combination with the platen of a typewriting machine of a label clip, comprising a thin metal plate adapted to lie close to the periphery of the platen and having at one end an angular extension, a lever to which said angular extension is secured, a bracket to which said lever is pivoted, means for detachably connecting the bracket 15 with a hub of the platen, and a spring for normally holding the clip close to the platen.

7. The combination with a platen, of a card holder, and a detachable connection for

the holder to the platen upon which connection the holder is pivotally mounted to 20 swing about an axis parallel with that of the platen.

8. A label clip for typewriting machines comprising a card holder adapted to lie close to the periphery of the platen and to 25 extend partway across it from one end, and means for pivotally mounting said holder at one end of the platen to move about an axis parallel with that of the platen, and for detachably connecting it therewith.

In testimony whereof, I have hereunto subscribed my name.

LEWIS C. MYERS.
